Specification for Design.

Patented Aug. 3, 1920.

Application filed February 20, 1920. Serial No. 360,161. Term of patent 14 years.

To all whom it may concern:

Be it known that I, FRANK H. CHELEY, a citizen of the United States of America, and a resident of Denver, in the county of Denver and State of Colorado, have invented a new, original, and ornamental Design for a Badge, Emblem, Insignia, or Article of Similar Nature for a Young Men's Christian Association Sweater Front, or for like Personal Wear, of which the following is a specification, reference being had to the accompanying drawing, forming part thereof.

The figure of the drawing is a face view of a badge, emblem, insignia, or article of similar nature applied to a portion of a textile fabric, embodying my new design.

I claim—

The ornamental design for a badge, emblem, insignia, or article of similar nature for a Young Men's Christian Association sweater front or for like personal wear.

FRANK H. CHELEY.
